UNITED STATES PATENT OFFICE.

ROBERT V. D. STOUTENBURGH, OF HOLLIS, NEW YORK.

HINGE-CLAMP.

No. 902,343.

Specification of Letters Patent.

Patented Oct. 27, 1908.

Application filed May 13, 1908. Serial No. 432,646.

To all whom it may concern:

Be it known that I, ROBERT V. D. STOUTENBURGH, a citizen of the United States, residing at Hollis, in the county of Queens and State of New York, have invented certain new and useful Improvements in Hinge-Clamps, of which the following is a specification.

This invention relates to a hinge-clamp especially adapted for use in connection with presses for pressing the wrinkles out of articles of clothing.

In the accompanying drawing, Figure 1 is an end view of a clothes press provided with hinged clamping devices made according to my invention; Fig. 2 is a side view of one of the hinged clamping devices, the movable clamping member being shown in one position in full lines and in another position in dotted lines; Fig. 3 is a top plan view of the clamping device with the members in closed position; Fig. 4 is an end elevation of the same, looking from right to left in Figs. 2 and 3; Fig. 5 is a similar view looking from left to right in Figs. 2 and 3; Fig. 6 is a side elevation, with the clamping members open, the cam for operating said members being removed, and indicated in dotted lines, and the hinge pin being shown in section; Fig. 7 is a similar view showing the clamping members partly closed.

Referring to the drawing, A indicates a suitable back or base for a clothes press and B and C indicate two flat boards or leaves, hinged to the sides of the back piece A and adapted to press against the trousers or other article of clothing which may be laid upon the back piece A. The particular construction of the members A, B and C form no part of my invention. In the press shown in the drawing, which is suitable for pressing trousers, the members B and C are each less than half the width of the member A so as to leave a gap between the members B and C for the seams of the trousers legs.

The back piece A and the leaves B and C are connected by hinged clamping devices D which form the subject of my invention. Each of these clamping devices comprises a member d, adapted for attachment to the stationary member of a clothes press, as for instance, the back piece A, and a movable member d' adapted for attachment to a leaf of the press. The member d of the hinge clamp, as shown, consists of an arm 1 and a hinge portion 2 projecting at right angles to

the arm, said hinge portion having a hinge-pin 3 extending through it and having a stop or guide 4 arranged at one edge of the hinge portion and between the arm 1 and the hinge-pin 3. The member d' consists of an arm 5 having a hinge portion 6 arranged substantially at right angles to said arm, said hinge-portion having a slot 7 extending therein, at right angles to the arm 5 and having flanges 8 and 9 opposite the ends of the slot. The hinge pin extends through the slot and connects the two members together. A substantially circular disk 10 is eccentrically mounted upon the hinge pin and arranged so that, when turned upon said pin, it will engage one or the other of the shoulders 8 and 9 on the member d', and move the hinge portion of the slotted member relatively to the hinge pin. This cam or eccentric 10 is of such diameter that when it bears against one of said shoulders it will be only slightly out of engagement with the opposite shoulder.

For convenience in turning the cam or eccentric 10, it is connected to a finger piece 11 by suitable means such as a rivet 12 and the hinge pin 3 also extends through the finger piece. As shown in the drawing, this finger piece consists of a piece of sheet metal having a part 11^a to which the eccentric is secured and a part 11^b bent over it at right angles to the part 11^a so that it can be conveniently grasped to turn the eccentric about the axis of the hinge-pin 3. The cam 10 and finger piece 11 might be made integral, instead of being riveted together. The arms d and d' may be of any shape suitable for attachment to the flat members or boards of a clothes press.

In operation, when the leaves of the clothes press are in open position, the cam 10 bears against the flange 9 of the hinge clamp, and the flanged end 8 of the member d' rests against the stop 4 on the member d, as indicated in Fig. 6. In this figure the hinged portion 6 is moved to the left by the cam so that the end 7^a of the slot is against the hinge pin. After an article of clothing has been placed on the base A of the press the leaves B and C are folded inwardly and during this folding operation the member d' of each clamp turns about the hinge pin, as a center, the cam 10 still remaining in engagement with the flange or shoulder 9 and holding the end 7^a of the slot in engagement with the hinge pin. In other words, in moving the leaves of the press to the horizontal position,

which is done by taking hold of the leaves and turning them inwardly, the cam is not moved relatively to the flange or shoulder 9, and the member d' therefore turns about the 5 pin 3, like an ordinary hinge member. When the member d' is folded over into the horizontal position, the flanged end 8 of the member d' is at first slightly above the stop 4, as shown in Fig. 7, but a slight movement of the 10 finger piece causes the cam to engage the shoulder 8 and move the lower end of the hinge portion 6 downward, as shown in dotted lines in Fig. 2 so that the edge 6^a of said hinge portion will engage the stop. The 15 further rotation of the cam, by means of the finger piece, will cause the member d' to move toward the member d , as shown in full lines in Fig. 2, and the clothing between the 20 back piece of the press and the leaves will thereby be pressed. During this movement of the members d and d' toward one another, the hinge portion 6 slides upon the hinge portion 2 until the end 7^b of the slot is in engagement with the hinge pin, providing the members 25 are brought as close together as possible. This, however, is determined by the thickness of the garment in the press. The pressure exerted upon the arm d' of the clamping device by the clothing in the press causes the 30 edge 6^a of the hinge portion 6 to bear against the guide or stop 4 and thus lock the parts in any position of adjustment. To open and close the press it is merely necessary to turn the finger piece so as to cause the cam to 35 swing around the axis of the hinge pin until the hinge portion 6 is raised above the stop 4, when the member d' may be swung into the position shown in Fig. 6.

It will be seen that my invention has the 40 functions of both a hinge and a clamp. The parts are preferably made of sheet metal, and bent to the proper forms, the stop 4 and the shoulders 8 and 9 being made by flanging the metal.

45 What I claim is,—

1. In a hinge clamp for clothes presses, the combination of a member having a hinge pin, a member having a slot engaged by said pin and a cam rotatably mounted on one of said 50 members and adapted to engage shoulders arranged upon the other member at opposite ends of said slot.

2. In a hinge clamp for clothes presses, the combination of a member having a hinge pin, a member having a slot engaged by said pin and a rotatable disk eccentrically mounted on one of said members and adapted to engage shoulders arranged upon the other member at opposite ends of said slot.

60 3. In a hinge clamp for clothes presses, the combination of a member having a hinge pin, a cam rotatable about the axis of said

pin, and a member having a slot engaged by said pin and having shoulders at the ends of said slot adapted to be engaged by said cam. 65

4. In a hinge clamp for clothes presses, the combination of a member having a hinge pin, a disk eccentrically mounted upon said pin, and a member having a slot engaged by said pin and having shoulders at the ends of 70 said slot adapted to be engaged by said disk.

5. A hinge clamp for clothes presses, comprising a member having a hinge pin and a stop and a member having a slot engaged by said pin, said latter member being adapted 75 to engage the stop in the closed position of the clamp and a cam rotatable about the axis of said pin and adapted to move the slotted member relatively to the pin.

6. A hinge clamp for clothes presses, comprising a member having a hinge pin and a stop and a member having a slot engaged by said pin, said latter member being adapted to engage the stop in the open and closed positions of the clamp, and a cam rotatable 85 about the axis of said pin and adapted to move the slotted member relatively to the pin.

7. A hinge clamp for clothes presses, comprising a member having a hinge pin and a 90 stop, and a member having a slot engaged by said pin, said latter member being adapted to engage the stop in the closed position of the clamp and having shoulders arranged at opposite ends of the slot, and a cam rotatable 95 about the axis of said pin and adapted to engage said shoulders to move the slotted member relatively to the pin.

8. A hinge clamp for clothes presses, comprising two arms having laterally projecting 100 hinge portions, one of said hinge portions having a hinge-pin and a stop, the other hinge portion having a slot extending lengthwise thereof and engaged by said pin and having shoulders at the ends of the slot, and an eccentric mounted on said pin and adapted 105 to engage said shoulders, said last mentioned hinge-portion being adapted to engage said stop in the closed position of the clamp. 110

9. A hinge clamp for clothes presses, comprising the member d having the hinge-portion 2, the stop 4, the member d' having the hinge portion 6, slot 7 and shoulders 8 and 9, the hinge pin 3 extending through said slot, 115 and the cam 10 and finger piece 11 rotatable about the axis of said hinge pin.

In testimony whereof I affix my signature, in presence of two witnesses.
